UNITED STATES PATENT OFFICE.

ALFRED G. CAMERON, OF LOS GATOS, AND CHARLES F. CAMERON, OF SAN FRANCISCO, CALIFORNIA; SAID CHARLES F. CAMERON ASSIGNOR TO SAID ALFRED G. CAMERON.

WALL STRUCTURE.

1,408,983.

Specification of Letters Patent.

Patented Mar. 7, 1922.

Application filed July 21, 1919. Serial No. 312,114.

To all whom it may concern:

Be it known that we, ALFRED G. CAMERON and CHARLES F. CAMERON, subjects of Great Britain, and residents, respectively, of Los Gatos, county of Santa Clara, and of the city and county of San Francisco, both in the State of California, have invented a certain new and useful Wall Structure, of which the following is a specification.

10 The invention relates to wall and ceiling structures and especially to such structures made of fiber board or "wall-board."

An object of the invention is to provide a fiber board wall structure or ceiling structure in which the fiber board is fully controlled.

Another object of the invention is to provide a fiber board wall structure which eliminates the necessity of battens and over 20 which wall paper may be placed.

A further object of the invention is to provide a strong and rigid fiber board wall structure.

The invention possesses other advantageous features, some of which, with the foregoing, will be set forth at length in the following description, where we shall outline in full, that form of the invention which we have selected for illustration in the drawings accompanying and forming part of the present specification. In said drawings we have shown two forms of wall structure, but it is to be understood that we do not limit ourselves to such forms, since the invention, 35 as expressed in the claims, may be embodied in a plurality of other forms.

Referring to said drawings:

Figure 1 is an elevation of a partly finished and partly unfinished wall structure 40 of our invention, portions thereof being broken away to better disclose the construction.

Fig. 2 is a similar view of a modified form of structure.

45 Our invention is applicable to wall structures and ceiling structures, and in the specification and claims we shall designate it as a wall structure, but it is to be understood that the expression "wall structure" 50 includes ceiling structures. Fiber board or "wall-board" has a very definite fiber grain, that is, the fibers all lie in substantially the same direction, and the fiber board has much greater strength and rigidity along the line 55 of the fibers than it has along a line normal

to the line of the fibers. Also, the expansion and contraction of fiber board occurs almost entirely along the line normal to the line of the fibers. Heretofore it has been the practice to apply the fiber board in large sheets with the grain of the board parallel to the grain of the studding, thereby placing the weakest section of the board at right angles to the studding and causing the expansion and contraction to occur along lines at right angles to the studding. The edges of the board are nailed to the studding, and consequently, battens must be employed to cover the spaced joint between the edges and expansion of the board would cause warping, so that there was no control of the board after it had been placed, and the board could not be papered over.

In accordance with our invention, we cut the sheets of fiber board into relatively narrow widths, forming strips, with the grain running lengthwise of the narrow sheets, and apply the board to the wall studding, with the grain of the board normal to the grain of the studding. The studding provides the necessary vertical strength to the wall and the fiber board, placed in accordance with our invention, provides the necessary longitudinal strength. The narrow strips do not vary their length under variations of temperature or humidity, since the grain runs lengthwise of the strips and the longitudinal edges of the strips are free and spaced from each other, so that expansion and contraction will not cause warping. Further, by making the strips narrow, the amount of expansion or contraction of each strip is very small, and does not produce any warping or pulling.

In accordance with our invention, the fiber board or wall-board, which may or may not be waterproofed, is cut into or formed into relatively small strips 2, for instance about four feet long and one foot wide with the fibers or grain of the board running in the direction of the length of the strip or panel. These strips are arranged longitudinally of the wall and are secured at their ends to the studding 3, in which the grain runs vertically. The grain of the strip is, therefore, normal to the grain of the studding. The strips are preferably of such length that they span three studs and are preferably staggered, so that each alternate panel extends to the next stud, as shown

in the drawings. The strips or panels are disposed longitudinally and are arranged one above the other, with a small gap or crack 4 between their longitudinal edges to permit expansion and are secured to the studs by nails and since there is no longitudinal movement of the ends of the panels, they can be nailed closely.

The structure is further strengthened and the movement of the panels in the direction of their width is controlled by vertically disposed reinforcing fiber sheets 5, pasted or glued to the strips. The reinforcing sheets are preferably of a width equal to the spacing of the studs and the grain of the fiber sheets is normal to the grain of the strips. These sheets may be of any desired thickness, but we prefer to make them thinner than the strips or panels. The sheets are secured over their entire surface to the strips, and since the grain in the strips is normal to the grain in the sheets, there is no movement or contraction in the width of the sheet and consequently they may be arranged with their vertical edges abutting, thereby eliminating the necessity of battens. By crossing the grain of the studs, strips and sheets, we have a three-ply construction, which makes the finished wall inert and self-controlled, so that it may be safely papered or painted without fear of opening seams or buckling wall sections.

In Fig. 2, we have shown a modified construction, which results in the production of a stronger and more rigid wall. In this construction, diagonally disposed sheets 6 with the grain running in the direction of the length of the sheets are pasted or glued

to the strips 2 with the edges of the diagonal sheets in abutment or substantial abutment. Over the diagonal sheets, the vertical reinforcing or surface sheets are adhesively secured, as in the construction shown in Fig. 1. The various fiber panels and fiber sheets may be waterproofed or not, as desired.

We claim:

1. A wall structure including studding strips of narrow fiber board which are substantially inexpandable longitudinally and are secured to the studding in slightly spaced relation laterally; and a covering of relatively wider fiber sheets laid on the strips at right angles thereto and in close lateral relation to form a continuous facing and being adhesively secured throughout the area of contact with the strips so that lateral expansion of the strips and sheets is prevented and buckling of the wall face avoided and a smooth outer face maintained.

2. A wall which consists of studding, narrow strips of longitudinally inexpandable fibrous board secured to the studding in offset courses; and an adhesively secured covering of relatively wider fiber sheets so that the contacting faces of the strips and sheets are mutually secured throughout their area, whereby a rigid, plane wall body is secured.

In testimony whereof, we have hereunto set our hands at San Francisco, California, this 11th day of July, 1919.
